UNITED STATES PATENT OFFICE

148,434

DESIGN FOR A COMBINATION COMPASS, PROTRACTOR, AND RULER

William E. Owen, Jr., Cedar Rapids, Iowa

Application March 22, 1946, Serial No. 127,804

Term of patent 14 years

(Cl. D52—1)

To all whom it may concern:

Be it known that I, William E. Owen, Jr., a citizen of the United States, residing at Cedar Rapids, in the county of Linn and State of Iowa, have invented a new, original, and ornamental Design for a Combination Compass, Protractor, and Ruler, of which the following is a specification, reference being had to the accompanying drawing, forming part thereof.

In the drawings:

Figure 1 is a face view of a combination compass, protractor, and ruler, showing my new design, and

Figure 2 is an edge view of the same.

I claim:

The ornamental design for a combination compass, protractor, and ruler, as shown.

WILLIAM E. OWEN, JR.
